(57) **CLAIM**

The ornamental design for a wireless network coordinator, as shown and described.

DESCRIPTION

FIG. 1 is a front perspective view of a wireless network coordinator showing our new design;

FIG. 2 is a front elevational view thereof;

FIG. 3 is a rear elevational view thereof;

FIG. 4 is a bottom side elevational view thereof;

FIG. 5 is a top side elevational view thereof;

FIG. 6 is a right elevational view thereof; and,

FIG. 7 is a left elevational view thereof.

Surface shading in the FIGS. 1-7 is provided to show clearly the character and contour of all surfaces of any three-dimensional aspects of the design.

The broken lines shown in the FIGS. 1-7 are for illustrative purposes only and forms no part of the claimed design.
